UNITED STATES PATENT OFFICE.

VLADIMIR K. ZWOYKIN, OF SWISSVALE, PENNSYLVANIA, ASSIGNOR TO WESTINGHOUSE ELECTRIC & MANUFACTURING COMPANY, A CORPORATION OF PENNSYLVANIA.

TELEVISION SYSTEM.

Application filed May 11, 1927. Serial No. 190,481.

My invention relates to picture-transmission systems and particularly to provisions for scanning the scene at the sending station and to provisions for recombining the elements thereof into a picture at the receiving station.

Many scanning and recombining devices in the prior art are made depending upon some rapidly moving element. If this element possesses inertia, the mechanical considerations which have heretofore placed a limit upon the rapidity of the movement have prevented the use of systems including such devices for television, because the time required for analysis by the scanning device and for recombination in the reproducing device could not be made small enough to permit the transmission of a dozen or more pictures per second.

It is an object of my invention to provide a scanning device and a recombining device in which sufficient rapidity of operation can be obtained without requiring prohibitively high speed of movement of the moving parts.

It is a further object of my invention to provide an optical means whereby the beam of light in the recombining device at the receiving station or the corresponding optical path in the scanning device may be moved with a high rapidity, although the movement of the moving optical parts is only of moderate speed.

It is a further object of my invention to provide an optical device in which the only moving parts rotate about one common axis and do not extend to any very great distance from said axis, whereby centrifugal forces are reduced to a minimum.

It is a further object of my invention to provide a picture-transmission system of the type comprising rotating parts in which the system can obtain the advantages of compound lenses.

It is a further object of my invention to provide such an optical device in which the light path is caused to make an angle with said axis of rotation.

It is a further object of my invention to provide means for varying aforesaid angle.

It is a further object of my invention to provide stationary optical means so cooperating with the movable optical means that

a plurality of lines in the scene or in the reproduced picture are traced during each revolution of the apparatus.

It is a further object of my invention to produce such compound movement of the light path that its trace upon the scene, or on the reproducing screen, will be a spiral.

It is a further object of my invention to ensure not only that successive repetitions of the spiral will not coincide but that a later spiral will never fall on exactly the location of an earlier one. By this means, a greater reproduction of detail is secured with the same number of lines per inch than has heretofore been possible.

It is a further object of my invention to select those portions of said spiral in which the reproduction of the illumination is but little distorted and to reproduce the picture by means of said selected portions.

It is a further object of my invention to provide means whereby said selected portions of the spiral may be brought into superposed position.

It is a further object of my invention to provide for said superposition by means of a stationary optical apparatus.

It is a further object of my invention to provide two rotating optical parts driven by a common motor and to provide adjustable means for causing the speed of rotation of one of said parts to differ from that of the other by a controllable amount.

Other objects of my invention will be apparent from the following detailed description and the accompanying drawings in which,

Figure 1 is a vertical section through one form of the recombining apparatus.

Fig. 2 is a vertical section through one form of the scanning apparatus.

Fig. 3 is a spiral illustrating the form of the trace of the light path upon the scene or upon the screen.

Fig. 4 is a diagram illustrating the optical principles employed in the invention.

Fig. 5 is a front view and Fig. 6 is a section of the prism shown near the middle of Fig. 4.

Fig. 7 is a diagram illustrating the relation of the prism to the spiral.

Fig. 8 is a diagram illustrating the effect of said prism.

Fig. 9 is a front view and Fig. 10 is a section of an assemblage of prisms constituting a modification of the prism illustrated in Figs. 4 to 6.

Fig. 11 is a diagram illustrating the relation of the assembled prisms to the spiral and the effect of the prisms.

Fig. 12 is a diagram illustrating the optical principles involved in that form of the invention which employs the prisms shown in Figs. 9 and 10.

Fig. 13 is an optical diagram illustrating a modification in which reflectors are used instead of refracting prisms; Fig. 13 is a diagrammatic section upon the line 13-13 of Fig. 14, and

Fig. 14 is a view of the assembled reflecting prisms. Diagrammatically, Fig. 14 is a section upon the line 14-14 of Fig. 13.

In Fig. 1, the light from the lamp 1 is concentrated by means of the condenser lens 2. The diaphragm 3 restricts the light to a small beam. The beam passes through a prism 4 and a prism 5 in series. Each of these prisms has curved surfaces in order that it may act both as a lens and a prism.

The light after passing through the two prisms impinges upon a screen 6. This may be a translucent screen, as illustrated, or it may be a distant screen to be viewed by spectators in a room. In the form illustrated, the screen is movably mounted, a bellows 7 being provided to accommodate the movement.

The prism 4 is mounted in the rotor 10 of a motor, preferably of the squirrel-cage type. Ball bearings 11 are provided for accurately centering the rotor relative to the stator 12 and for preventing frictional resistance to its movement.

The rotor 10 has a central opening lined by a steel tube 13 in which the prism 4 is mounted. A similar steel tube 14 in alignment with the tube 13 carries the prism 5. This tube is supported by a supplemental rotor 15 supported through ball bearings 16 in a hub 17 which is magnetically continuous with the stator 12. The stator 12 is provided with the usual windings for causing a rotating field.

The rotor 10 is preferably of the slotted type, with squirrel-cage conductors in the slots to ensure that it will rotate in synchronism with the rotating field established by the windings of the stator. The rotor 15, however, is preferably unslotted and receives but little torque directly from the rotating field through the hub 17. It does, however, receive a torque by the magnetic drag between the telescoping portions of the tubes 13 and 14. If the very slight friction of the ball bearings 16 were the only load on rotor 15, this magnetic drag would be sufficient to cause the two rotors to be synchronous.

In order that the rotor 15 shall not run at the same speed as the rotor 10, the rotor 15 is provided with a conductive disc 18, preferably

of aluminum which extends between the poles of a permanent magnet 19, adjusted by means of a screw 20. The action of the magnet upon the disc serves to retard the prism 5, whereby it rotates at a somewhat slower speed than the prism 4.

The relative position of the two prisms is, therefore, changing, although both are rotating at a higher speed than the rate of said relative motion.

Fig. 2 illustrates the scanning device. The details of the scanning device are analogous to the details of the reproducing device illustrated in Fig. 1, and certain modifications illustrated in Fig. 2 may equally well be applied to the reproducing device.

The lens 30, through which the scene is focused, is analogous in its position in the optical system of Fig. 2 to the screen 6 in Fig. 1. The lens 30 is preferably an achromatic lens. The prism 31 is mounted in a rotor 32 just as the prism 4 is mounted in the rotor 10. The stator 33 is provided with a projecting hub 34 supporting a second rotor 35 for moving a second prism 36 as the prism 5 in Fig. 1 is moved. The prism 36 is retarded by means of a conducting disc 37 and an adjustable magnet 38 corresponding to disc 18 and magnet 19 in Fig. 1.

The prisms 31 and 36, instead of being provided with curved surfaces to act as lenses, are ordinary prisms and the lens action is obtained by the lens 30. The lens 40 at the right of the prisms is optically analogous to the lens 2 in Fig. 1. It may be adjusted by means of screws 41 for correcting the focus.

A housing 42 which encloses the optical portion of the apparatus is provided with an open end through which the screws 41 may be reached for said adjustment. A flange 43 is provided at the right of the casing in order that the apparatus which is put in place after the focusing is performed shall be definitely positioned.

The light-sensitive apparatus which is to cooperate with the scanning device is contained in a housing 44, one face of which abuts against the flange 43, thereby fixing the distance of the apparatus from the lens 40 definitely. A small window 45 in the housing 44 admits light from the lens 40 to the light-sensitive apparatus.

The light-sensitive apparatus is represented as a photo-electric cell 46 combined with a thermionic amplifier 47. It will, however, be understood that the photo-electric cell and the amplifier can be separated if desired and it will also be understood that any other light-sensitive apparatus may be used if preferred.

The system by which the light emitted from the lamp 1 is made to correspond in intensity to the illumination of the photo-cell 46 is not part of the present invention and, therefore, is not described in detail. Any

system by means of which, instant by instant, the light supplied to the reproducing apparatus is made to correspond to the illumination of the light-sensitive apparatus in the scanning device may be used.

Since the forms of my invention illustrated in Figs. 4 to 14 will be more readily understood after the explanation of the operation of the apparatus illustrated in Figs. 1 and 2, this operation will be described before describing the structure of said forms.

In any optical system, if the point which the light finally reaches be considered as if it were a source of illumination, the imaginary light from said source will arrive at the point from which the real light actually started. This principle will enable us to describe the operation of Fig. 2 more conveniently by tracing the light path backward, that is, by speaking as if the window 45 were a source of light.

The beam of light from the lamp 1 and the light through the optical system of Fig. 2 each travel along a light path. These light paths have many similarities although, because the beam from the lamp travels its path in a direction opposite to that in which the light entering the window 45 travels its path, these similarities are not easily expressed in words.

In the scanning device, the lenses 30 and 40 and the prisms 31 and 36 establish an optical path which at any instant connects some one point in the scene with the window 45 and so with the photo-cell 46.

The window 45 is at the principal focus of the optical system comprising lenses 30 and 40. The window 45, however, does not cover the whole field of these lenses but only one spot, which is so small, relative to the field, that it may be regarded as an element of the scene.

The path from the window 45 through the lenses would, if it were not for the prisms 31 and 36, reach the center of the scene. The prisms 31 and 36 act to bend the path of light, whereby the window 45 is associated with a point at one side of the center of the scene.

When the prisms 31 and 36 are in the relative position illustrated in Fig. 2, the diverting action of one prism is added to the diverting action of the other prism with the result that, as the prisms rotate together, the trace of the optical path upon the scene is a circle of large diameter.

Since the prism 36 rotates at a smaller velocity than the prism 31, the two prisms will not continue to be in the relative position illustrated in Fig. 2 and they will sooner or later arrive at a relative position in which the diverting action of one prism is exactly opposite that of the other. If the two diverting actions are equal, the resultant diversion of the light path is then zero and

the window 45 will be optically correlated to the center of the scene.

As the relative position of the prisms 31 and 36 changes gradually from that illustrated in Fig. 2 to that in which there is zero diversion, the trace of the optical path upon the scene will be a spiral.

The outmost whorl of the spiral will correspond to the relative position illustrated in Fig. 2 and the innermost whorl or the central point will correspond to the position in which there is minimum or zero diversion. The spiral as a whole will, therefore, cover the whole scene.

Any one whorl of the spiral will be traced in the time required for one revolution of the motor. The whole spiral will be traced from the outer whorl to the center in the time required for the prism 36 to lag behind the prism 31, one-half of a revolution.

During the time that the prism 36 lags, an additional half-revolution behind the prism 31, the spiral will be traced from the center to the outmost whorl. The whole picture is, therefore, covered twice in the time required for a single complete revolution of one prism relative to the other. If, for example, the prism 36 rotates eight turns per second slower than the prism 31, there will be sixteen complete explorations of the scene per second.

The spiral traced from the center outward will not coincide with that traced inward. To clearly show this the first few whorls of the spiral which begins at the center are shown in dotted lines in Fig. 3.

If the number of revolutions per second by which the speed of the prism 31 differs from that of the prism 36 is not a whole number, the spiral traced by the optical path from the center outward will not coincide with the next spiral traced in the same direction. The spiral traced during any one half-period of the relative rotation will correspond with a previous spiral traced a number of periods of the relative rotation earlier equal to the denominator of the fraction expressing the number of turns per second by which one rate of revolution differs from the other.

Moreover, if the rate of revolution of one prism is incommensurate with the rate of revolution of the other, there will never be two spirals which exactly coincide. It is, therefore, evident that by properly adjusting the magnet 38, the scanning device may be made to explore the whole picture, instead of merely exploring certain lines.

Consider the combined deflecting action of the prisms 31 and 36 when they are in a position intermediate the position illustrated in Fig. 2 and the position of zero deflection. When, for example, the prism 31 produces a deflection upward and the prism 36 produces a deflection obliquely upward and to the right, the actual position in the scene of the

trace of the optical path is a spot at the end of the resultant obtained by adding the two displacements vectorially.

When the prisms are nearly, but not exactly in the position illustrated in Fig. 2, the change in the length of this resultant is slow. When the two deflections are approximately at right angles to each other, the change in the length of the resultant is more rapid, but the rate of said change is nearly uniform.

When one of the two displacements is nearly opposite the other, the resultant is nearly zero and the length of it is changing very rapidly.

At each instant the length of the resultant displacement is the radius of the spiral. It is, therefore, apparent that, near the outer part of the spiral, the whorls are closely packed. In the intermediate portion of the spiral, the whorls are more widely separated. At this part of the spiral, the whorls are nearly uniformly spaced. Near the center of the spiral, the spacing of the whorls is wider but here the spacing is also changing more rapidly.

At the outside of the spiral where the whorls are closely spaced, the linear velocity of the spot of light on the screen, or of the corresponding area in the view, is large. The illumination of the screen by the moving spot of light while traversing unit length of arc near the outside of the spiral is therefore small. Likewise the illumination of the window 45 from that portion of the scene along unit length of arc near the outside of the spiral is small because that portion of the scene is traversed quickly.

The increase in number of turns of spiral and the increase in speed along the lines thus tend to offset each other, but they do not do so completely because the two do not change according to the same law. Best results are therefore obtained from those parts of the spiral where the spacing of the lines is nearly uniform.

The stator 12 in Fig. 1 and the stator 33 in Fig. 2 are preferably provided with current from a common source. The two motors will, therefore, rotate in synchronism. By temporarily increasing the retardation upon the disc 18 or the disc 37, the relative rotation of the prisms 4 and 5 can be brought into synchronism with the relative positions of the prisms 31 and 36. After this has been accomplished, the movements of the scanning device and of the reproducing device will be synchronous.

Consequently, as the light path in the scanning device traces a spiral in the scene, the light beam in the reproducing device will trace a spiral upon the ground glass 6, or, if the reproducing device is a projector of the stereopticon type, it will reproduce the spiral upon the screen before the spectators. The

two spirals correspond both in time and in position.

Because the brightness of the light from the lamp 1 is made to correspond at each instant to the illumination of the photo-cell 46 the illumination of the screen at any point of the spiral traced thereon will correspond to the brightness of that spot in the scene which corresponds to the selected point on the screen. The distribution of the illumination on the screen will therefore correspond to the distribution of brightness in the scene and the result of simultaneously tracing the two spirals is a reproduction of the view upon the screen.

This reproduction, however, will not be faithful because where the whorls of the spiral are close together, illumination upon the screen will not be in the proportion that correct reproduction requires. In order to remedy this defect, certain portions only of the spiral are used either to illuminate the window 45 in Fig. 2 or to reproduce the picture on the screen. The simplest way of accomplishing this result is illustrated in Figs. 4 to 8.

In explaining the system illustrated in Fig. 4, the operation will be described in terms of the projecting or recombining apparatus. It is equally applicable to the scanning apparatus but mention thereof is, for the most part, omitted to avoid confusion. The dotted lines of Fig. 4 represent the boundary of the light beam from the point 51 which corresponds to the opening in the screen 3 of Fig. 1. The lenses 52 and 53 represent the action of the curved surfaces of the prisms 4 and 5. This action is accomplished by two separated lenses in order that the prism 56 may be inserted between them.

The prisms 54 and 55 correspond to the prisms 4 and 5 in Fig. 1, but there is a difference in their design. When the prisms 54 and 55 are in that relative position in which they produce minimum deflection, the deflection is not zero. The maximum deflection is obtained when the prisms are in the relative position illustrated in Fig. 4, and the corresponding light path is represented by the dotted lines *a*. The minimum deflection is obtained when the position of the prism 55 relative to that of the prism 54 differs from the illustrated position by 180°. The path having minimum deflection is illustrated by the dotted lines *b*.

Between the prisms 54 and 55 a double prism 56 is provided. This prism is stationary. Its upper half tends to deflect light downwardly and its lower half tends to deflect light upwardly. In Fig. 5, the prism 56 is shown in front view and its outline is represented as circular. This is not a necessary configuration, but the outline should be made to conform to the shape of the margin of the picture. In Fig. 6, the prism is shown

in section. The edges of the prism are at the top and bottom and the thickest portion is at the center.

In Fig. 7, a spiral is shown with its innermost turn corresponding in diameter to the inner boundary of that portion of Fig. 3 in which the whorls are too widely spaced. Fig. 7 does not represent the trace of the light upon the screen, but represents the form which said trace would have if the prism 56 were not provided. The innermost whorl of Fig. 7 corresponds to that relative position of the prisms 54 and 55 which produces minimum deflection.

The upper dotted rectangle 57 in Fig. 7 corresponds to the position upon the screen which would, if the prism 56 were absent, be reached by the light which, in fact, passes through the upper half of the prism 56 and the rectangle 58 represents the corresponding position for the lower half of the prism 56. The action of the prism 56 brings the light which otherwise would reach the rectangle 57 into the central position 59 and the lower half of the prism 56 brings the light which would otherwise occupy the rectangle 58 into the same position 59.

The two positions 57 and 58 are, consequently, made to occupy the same central position 59, but the whorl-arcs therein do not coincide. This is illustrated in Fig. 8 in which the closely spaced arcs 61 correspond to the closely spaced whorls near the bottom of the position 58, while the closely spaced arcs 62 correspond to the closely spaced whorls near the top of the rectangle 57.

The top of the picture, in both instances, is at the top of Fig. 8. The two rectangles 57 and 58, therefore, correspond to two scannings of the scene or to two recombinations thereof which can be superposed without producing lack of registry. Moreover, the over-illumination in the rectangle 57 is brought into the same position as the under-illumination in the rectangle 58 and the over-illuminated part of the rectangle 58 is superposed upon the less-illuminated part of the rectangle 57. The two tend to correct each other and, consequently, unless the rectangles are originally positioned so that they extend into portions of the spiral where the whorls are too badly crowded, a satisfactory reproduction may be obtained over the whole picture.

It is possible, on the principle that any optical system is reversible, to explain the application of Fig. 4 to a scanning device by regarding the point 51 as the window 45 and the light as traveling from the right-hand end of Fig. 4 toward the left. Such an explanation would not, however, correspond to a practical arrangement of the apparatus because it would require certain parts to be too large.

An application of Fig. 4 to the scanning apparatus which avoids this difficulty may be

made by regarding the point 51 as a source of light in the landscape or other object viewed by the scanning apparatus. The lens 52 then corresponds to the lens 30, the prisms 54 and 55 to the prisms 31 and 33 and the lens 53 to the lens 40. The prism 56 may be inserted either between prism 36 and lens 40 or between two members of a compound lens system equivalent to the lens 40.

As the lenses 30 and 40 form an image of the view on the wall of the casing 44 containing window 45, so the lenses 52 and 53 form on the screens at the right of Fig. 4 an image of the landscape or other view.

Also, as the motion of the prisms 31 and 36 causes the image to move over the wall, associating the window 45 with points along a spiral in the image, so the prisms 54 and 55 cause the image to move on the screen. If a stationary point be selected in the screen to correspond to window 45 the motion of the image over the screen will associate it with points arranged along paths in the image. The action of the prism 56, displacing the image during two portions of each whorl, the path traced in the moving image by the fixed point will not be a spiral but a network like that shown in Fig. 8.

The apparatus illustrated in Fig. 1 and Fig. 2 affords only two complete scannings of the view and recombinations of the picture for one cycle of the relative movement of the prisms, while the system illustrated in Figs. 4 to 8 provides four complete scannings in such a cycle. The number of lines traced in the picture for a single revolution of the pair of prisms when using the system illustrated in Figs. 4 to 8 is double the number obtained by the system illustrated in Figs. 1 and 2.

Moreover, as is best shown in Fig. 7, the illumination of the photo-cell is not employed for controlling the brightness upon the screen during the whole of the revolution. It is, therefore, possible to use the time when the optical system is in the position represented by the right-hand and left-hand segments of Fig. 7, for other purposes. For example, it may be used to control synchronizing devices.

In Figs. 9 to 12, another example of this principle is illustrated in which, instead of one pair of prisms like the prism 56, three pairs are provided. The six prisms may very conveniently be built as a unit. Figs. 9 and 10 illustrate this unit.

The glass member 70 comprises a flat central portion 71 which is optically inactive, and six wedge-shaped marginal portions 72 which provide the prismatic effect. In order that the prisms 72 shall not cause the light to break up into colors, they are corrected by combining therewith, six prisms 73 of glass having a different index of refraction and a different degree of dispersion from the glass 70. By so choosing the angles of the prisms 72 and 73, that the dispersion is corrected for certain se-

lected wave lengths, the correct diversion may be obtained for the combination thereby avoiding undesirable chromatic effects.

At one side of the sixfold prism, a mask 75 is provided. This mask has six circular holes 76 which are concentric with the six prisms, respectively. Preferably these circles 76 are nearly tangent to one another at the junctions of the prisms.

10 The opaque portions of the mask 75 cut out the light from those portions of the spiral which, when deflected to the central position, would produce picture elements not in registry with the corresponding elements from the 15 other prisms. A very narrow zone can, theoretically, be broken into a great many portions and the portions separately deflected to a central position, without producing lack of registry. Zones of any substantial radial 20 width require that the number of separately deflected portions be limited.

The greater the number of repetitions of the view which are provided for by the plurality of prisms, the smaller will be the area 25 in each prism which can be used to form the central reproduction, without producing lack of registry among the overlapping reproductions. I have found by computation and experiment that no further advantage is obtained by increasing the number of prisms 30 above six.

In Fig. 12, the optical action of a system involving the sixfold prism is represented. The point 80 in Fig. 12 represents the window 45 of Fig. 2 or the opening in the shutter 3 of Fig. 1. The lenses 81 and 82 represent an optical system corresponding to the lens 40 in Fig. 2 or to the lens action of the prisms, in Fig. 1.

40 The lens 81 is shown as made of two lenses cemented together to correct chromatic aberration. The lens 82 is shown as made by two lenses for the same reason, but certain optical advantages are obtained by having this 45 pair spaced apart. The combination of four lenses enables much better focusing, both as to color effect and as to flatness of field, than can be obtained with a single lens. Since the lens system is stationary, no difficulties result from the use of a plurality of lenses in the system even though some of them are 50 spaced apart.

The rotating prisms 83 and 84 correspond to the rotating prisms 4 and 5 in Fig. 1 or 55 to the rotating prisms 31 and 36 in Fig. 2.

These prisms are shown as each composed of two pieces of glass in order that chromatic effects may be corrected as explained when discussing the combination of prisms 72 and 60 73 in connection with Fig. 10. The sixfold prism 70 and the mask 75 in the central part of Fig. 12 represent the structure already described in connection with Figs. 9 and 10.

The dotted lines in Fig. 12 represent the 65 boundaries of the light beam. The lines a

correspond to the position of the light beam in the reproducing apparatus or of the optical path in the scanning apparatus when the prisms are in the position for maximum diversion and the dotted lines b correspond 70 to the position when the prisms 83 and 84 are in the position for minimum diversion.

In Fig. 11, the blank portions 87 correspond to the spaces masked by the screen 75. The circles 88 represent the positions in the scene 75 or on the screen which would result if the sixfold prism were not present and the central circle 89 corresponds to the result of the action of the sixfold prism upon the spiral. It will be observed that near the center of 80 the circle 89, the several lines are practically uniformly distributed, while near the edges of the circle, closely packed lines from certain circles 88 are superposed upon widely spaced lines from the diametrically opposite 85 circles 88. It will, therefore, be evident that the illumination will be represented with reasonable faithfulness over the whole picture.

It is also evident from inspection of the circle 89, that the number of lines traced 90 therein is six times as great as the number of lines traced in Fig. 3. Consequently, the arrangement employing a sixfold prism will enable pictures to be reproduced six times as rapidly or, stated another way, for the same 95 rapidity of scanning and reproducing, an apparatus may be used in which the speed of rotation is only one-sixth as great as would otherwise be necessary.

In Figs. 13 and 14, a modification of the 100 apparatus illustrated in Figs. 9 to 12 is shown. The lens system shown at 81 and 82 is as in Fig. 12. The rotating prisms 83 and 84 also correspond to Fig. 12. Six trains of lenses 90 and 91 are provided for bringing 105 the rays of light energy from the prism 84 into the condition of parallel beams.

Like the lenses 81 and 82 the lenses 90 and 91 constitute lens systems which may include 110 lenses spaced apart. The lenses 90 act as condenser lenses, enabling the more inexpensive lenses 91 to be of small size. It is unnecessary to correct the lenses 90 for chromatic aberration because the lens system 91 is not at the focal plane of the lenses 90. These 115 large lenses are therefore of an inexpensive sort.

Instead of a sixfold prism corresponding to the unit 70, a set of six doubly-reflecting prisms is provided and one of the six systems of lenses cooperates with each of the 120 doubly-reflecting prisms respectively. The path of the light is represented by showing only the central ray in each lens train and the corresponding reflecting prism.

The upper prism 91 shown in section in Fig. 13 receives the light from the upper lenses 90, shown in section, through a face 93 at right angles to said light. The face 94 reflects the light by internal reflection, and 130

therefore without loss, onto the face 95 where it is again reflected in the same way, and it then emerges from the face 96.

The faces 94 and 95 are not parallel, consequently, the emerging beam is not parallel to the beam through the lenses 91. The difference in direction is such that the emerging ray is diverted toward the central part of the screen or of the view. A similar action is obtained in each of the six reflecting prisms. The result of the optical system shown in Fig. 13 is like the central part of Fig. 11 for the reasons which have been already explained in connection with Figs. 9, 10 and 12.

15 The projecting apparatus illustrated in Fig. 1 or analogous projecting apparatus made according to Figs. 4, 12 or 13 may be used for other purposes beside the reproduction of pictures upon the screen 6.

20 If the lamp 1 instead of varying its brilliance in accordance with the illumination at different points of the picture is of a steady brilliance, there may be substituted for the screen 6, a black and white picture.

25 If the black and white picture is a transparency, either the usual photographic negative or a lantern slide, the projecting apparatus will cause the different points of this picture to be illuminated in turn, and the light which emerges from the transparency will vary in intensity according to the density of the transparency at each point.

The light which emerges from the transparency may be collected by a lens or a lens 35 system and delivered to a small photo-electric cell or it may be received upon a large photo-electric cell or cells without being first collected. The current controlled by such photocell or photocells will then be like the 40 current controlled by the photocell 46 in Fig. 2, and may be used to control a distant picture reproducing apparatus.

Instead of a transparency, the black and 45 white picture may be opaque, and the photocell and lens system to be controlled by the light from the lamp 1 will then be upon the same side of the picture as the lamp 1 and will be affected by the light reflected from the picture. When the travelling spot of 50 light passes over a dark part of the picture, the photocell will be dark, and when the light from the lamp 1 passes over a white part of the picture, the photocell will be illuminated. At intermediate shades, the photocell will be 55 partly illuminated by the reflected light. The reflected light may be received in a lens system to control a small photocell, or a large photocell or number of photocells may be used, as with the transmitted light.

60 By this means, the apparatus shown in Fig. 1 may be used as a picture-sending device for either transparent or opaque black and white pictures.

It will be observed that although Figs. 12 65 and 13 show complicated optical arrange-

ments, the only moving parts are the prisms 83 and 84. Also in the simpler system illustrated in Figs. 1 and 2, the corresponding prisms 4, 5, 31 and 36 are the only moving parts. The system, therefore, has the advantage that high speed is possible.

The high speed of rotation will not be accompanied by sufficient centrifugal strains to interfere with the correct optical action of the prisms because they are of small dimensions and close to the axis of rotation.

The system has also the advantages that there is no great loss of light, that the speed necessary for reproducing pictures with a rapidity sufficient for television is not prohibitively high and that the faithfulness of the reproduction of the illumination throughout the whole picture is very uniform.

The incommensurable relation between the speeds of the two rotating prisms gives the advantage that the consecutive images presented on the screen are not repetitions of the same points in the view but of points closely adjacent thereto. This will result in greater actual detail if the screen is a photographic plate or in a greater perception of detail if the screen is for visual observation.

Although I have described only a limited number of modifications of my apparatus, it will be apparent to those skilled in the art that many changes come within the spirit of my invention and I, therefore, do not wish to be understood as indicating any limitations thereof except such as are required by the prior art or expressed in the claims.

I claim as my invention:

1. In an optical system for transmission of pictures, two light-deflecting devices, means for rotating one of said devices, means for rotating the other of said devices at a different speed dependent upon the speed of the first and means for adjusting the difference.

2. In an optical instrument, an electric motor comprising a stator and a hollow rotor, a second hollow rotor in alignment with the first, optical prisms, one in each rotor with faces across the axes thereof and means whereby the speed of one rotor will differ from that of the other.

3. In an optical instrument, an electric motor comprising a stator and a hollow rotor, a second hollow rotor in alignment with the first, optical prisms, one in each rotor with faces across the axes thereof and a brake retarding one of said rotors.

4. In an optical system, stationary means for establishing an optical path, light-deflecting means for establishing a second optical path continuous therewith and at an angle thereto, means for rotating said light-deflecting means to produce a rotation of said second optical path about the line of the first optical path and stationary means for deflecting light in said second optical path toward the line of said fixed optical path.

5. In an optical system, stationary means for establishing an optical path, light-deflecting for establishing a second optical path continuous therewith and at an angle thereto, means for rotating said light-deflecting means to produce a rotation of said second optical path about the line of the first optical path and means outside the line of said fixed optical path for deflecting light towards said line during at least a portion of said rotation.

6. In an optical system, stationary means for establishing an optical path, light-deflecting for establishing a second optical path continuous therewith and at an angle thereto, means for rotating said light-deflecting means to produce a rotation of said second optical path about the line of the first optical path and means outside the line of said fixed optical path and arranged symmetrically about said line for deflecting light towards said line during at least a portion of said rotation.

7. In a picture transmission system, an optical instrument having a window, means including moving optical parts for establishing an optical path connecting said window with areas lying along a spiral and stationary light-deflecting means cooperating with said first named means for establishing an optical path connecting said window with areas in a locus similar to portions of said spiral and displaced toward the center thereof.

8. In an optical instrument, a plurality of light-deflecting devices arranged about an axis and each so directed as to deflect light toward said axis and means for producing a beam of light oblique to said axis and for directing said beam upon each of said devices in turn.

9. In an optical system, means for establishing an optical path having a fixed direction, a pair of light-deflecting devices associated with said path to produce a light path continuous therewith and at an angle thereto, the deflecting power of said devices being unequal, whereby when they deflect in opposite directions the resulting deflection is finite.

10. In an optical system, means for establishing an optical path having a fixed direction, a pair of light-deflecting devices associated with said path to produce a light path continuous therewith and at an angle thereto, the deflecting power of said devices being unequal, whereby when they deflect in opposite directions the resulting deflection is finite and means for progressively changing the relative directions of said diversions.

11. In an optical system, means for establishing an optical path having a fixed direction, a pair of light-deflecting devices associated with said path to produce a light path continuous therewith and at an angle thereto, the deflecting power of said devices being unequal, whereby when they deflect

in opposite directions the resulting deflection is finite and means for progressively changing the relative directions of said diversions, each of said directions being at all times in a plane through said fixed direction.

12. In an optical system, means for establishing an optical path having a fixed direction, a pair of light-deflecting devices associated with said path to produce a light path continuous therewith and at an angle thereto, the deflecting power of said devices being unequal, whereby when they deflect in opposite directions the resulting deflection is finite and a light-deflecting device at one side of the line of said fixed path having a deflecting power at least equal to the difference of the deflecting powers of said pair of deflecting devices and directed to deflect light toward the line of said fixed path.

13. In an optical system, means for establishing an optical path having a fixed direction, a pair of light-deflecting devices associated with said path to produce a light path continuous therewith and at an angle thereto, the deflecting power of said devices being unequal, whereby when they deflect in opposite directions the resulting deflection is finite and a plurality of light-deflecting devices arranged about the line of said fixed path and directed to deflect light toward said line, each of said plurality having a deflecting power at least as great as the difference of the deflecting powers of said pair of deflecting devices.

14. In an optical system, means for establishing an optical path having a fixed direction, means for establishing an optical path continuous with said fixed path and making an angle therewith, said means being movable to vary both the plane and the size of said angle, whereby the second optical path moves within a space bounded by two coaxial cones, the common axis being in alignment with said fixed path and a plurality of light-deflecting devices within said space acting to deflect light toward said common axis.

15. In an optical system, means for establishing an optical path having a fixed direction, means for establishing an optical path continuous with said fixed path and making an angle therewith, said means being movable to vary both the plane and the size of said angle whereby the second optical path moves within a space bounded by two coaxial cones, the common axis being in alignment with said fixed path and a plurality of light deflecting devices with said space acting to deflect light toward said common axis, said light deflecting devices being effective throughout a portion only of the circumferential extent of said space.

In testimony whereof, I have hereunto subscribed my name this 29th day of April 1927.

VLADIMIR K. ZWORYKIN.
